(57) **CLAIM**

I claim the ornamental design for infant wear with no-skid elements, as shown and described.

DESCRIPTION

FIG. 1 is a front view of infant wear with no-skid elements.

FIG. 2 is a rear view of infant wear with no-skid elements.

FIG. 3 is top view of infant wear with no-skid elements.

FIG. 4 is bottom view of infant wear with no-skid elements; and,

FIG. 5 is a left side view of infant wear with no-skid elements. (The right side view being a mirror image of the left side view).

The broken lines form no part of infant wear with no-skid elements of FIGS. 1-5.
